CLAIM

The ornamental design for a liner for containers, as shown and described.

DESCRIPTION

FIG. 1 is a perspective view of a liner for containers showing the design.

FIG. 2 is a front plan view of the design of FIG. 1.

FIG. 3 is a back plan view of the design of FIG. 1.

FIG. 4 is a side view of the design of FIG. 1.

FIG. 5 is a side view of the design of FIG. 1.

FIG. 6 is a top plan view of the design of FIG. 1; and,

FIG. 7 is a bottom view of the design of FIG. 1.

In the drawings, the broken lines depict environmental subject matter only that forms no part of the claim.
